UNITED STATES PATENT OFFICE.

CHARLES W. WEST, OF SAN MATEO, CALIFORNIA.

DESIGN FOR AN AUTOMOBILE RADIATOR CAP OR SIMILAR ARTICLE.

Application filed December 24, 1928. Serial No. 29,398. Term of patent 14 years.

To all whom it may concern:

Be it known that I, CHARLES W. WEST, a citizen of the United States, residing at San Mateo, county of San Mateo, and State of California, have invented a new, original and ornamental Design for an Automobile Radiator Cap or Similar Article, of which the following is a specification.

The figure is a perspective view of an automobile radiator cap or similar article, showing my new design.

I claim:

The ornamental design for an automobile radiator cap or similar article as shown.

CHARLES W. WEST.
